Permit Andrew S. Stephen Austin, Bradf. N. H.

Letter Patent dated July 1, 1836. -

The Schedule referred to in theafore Letters Patent and making part of the same
Containing a description of the mode of the side. Elements and parts made Stephen
Austin himself of this improvement in the form and construction of cooking
Stove.

To all persons to whom these presents shall come,

Know, that, the Elements Austin and Stephen Austin of Bradf. in the
County of Merrimack and State of New Hampshire have invented a new and
useful improvement in the form and Construction of Cooking Stove, by a Stove
called Austin's & Austin's cooking Stove and the following is a full and exact
description of the construction and operation of said Stove as invented or improved
by us, etc.

1st. A fire box is constructed of any suitable dimensions say 2^{ft} in length 16
inches wide and 12ⁱⁿ high with oval or flat front or place and hearth of
suitable width.

2nd. In the same furnace with the fire box situated on each side are two departments for
cooking, one on each side of the fire box 20^{inches} in length 17ⁱⁿ wide and 18ⁱⁿ high
rising three inches higher than the fire box. In each of these departments is placed
an iron circular or square of cast iron or sheet with a flue laterally from the fire
box for a passage of the fire and heat to the top of the iron, down on the
side of the iron from the fire box under the iron below it and the hearth & the
fire box and continuing up between the iron and the fire box nearly to the
bottom of the flue at first starting.

The iron may be attached to the ends of the iron
spouts at the back part and the flues may be continued nearly around
the back part of the iron also; but it is best to have the back part of the iron
Circular and the end in a narrow space back the back side of the iron
nearly from the top to bottom of the iron. This will throw the heat therefrom
around the iron, or if the back of the iron be square a perpendicular partition
may be inserted in this place a part of it.

A circular partition is made to pass from the fire box about six inches from the back part of it behind the latrine, thus from the fire box, between the tops of the even and top of the stone, round to about the middle of the side of the stove, opposite to the fire box - forming a flue between the circular partition and the inside of the stove about 6 or 6 inches square, the tops of the even extending to the inside of the stove in this part to form the floor of this flue, except for 6 or 6 inches square next to the fire box, where it is left open for the smoke and heat to pass off to the main flue which is continued about six inches square across the back and upper part of the fire box to the middle of the back flue is the funnel for the smoke to pass off.

At the heads of these flues made by the circular partitions dampers are placed while being shut the smoke and heat pass down under and around the even up into the flue at the back part of the fire box and off by the funnel.

Dampers may also be placed at the mouths of the flues from the fire box so as to turn the heat all on one side by opening one and shutting the other. Dampers may also be placed just to the fire box so as to make when shut a part of the upper side circular partition while being open still form a more direct passage for the smoke when the heat is not wanted over the even, or the upper side. With a damper may also be constructed from the back part of the fire box to communicate immediately with the main flue, and the back and upper part of the fire box.

This fire is calculated for fire boxes one large directly over the fire box and two of smaller size over each even. These flues and partitions are then placed and arranged to equalize the heat around all parts of the even and at the same time to take the greatest advantage of the heat for other purposes.

That the claim or my invention is the arrangement and arrangement of the circular partitions and the arrangement of the even and the upper side flues for the purposes aforesaid. In testifying that the preceding is a true specification of my back improvement, also declare, he has been made at my house this eighth day of April A.D. 1836. E. D. & A. A. S.

In this behalf

Wm. A. Hoadley.
